UNITED STATES PATENT OFFICE.

CHARLES G. WILTSE, OF NEW YORK, N. Y.

POTATO-DIGGER.

SPECIFICATION forming part of Letters Patent No. 267,959, dated November 21, 1882.

Application filed July 29, 1882. (No model.)

To all whom it may concern:

Be it known that I, CHARLES G. WILTSE, a citizen of the United States, residing at New York, in the county and State of New York, 5 have invented new and useful Improvements in Potato-Diggers, of which the following is a specification.

This invention relates to that class of potato-diggers in which the tubers, together with 10 the earth, are received from the plow in the scoops of an elevator, whereby they are deposited on a delivery-chute, from which they roll on a laterally-reciprocating distributor, allowing a portion to pass through it, the re- 15 maining portion passing over its edge, whence they fall into a receptacle having two compartments.

My invention consists in the novel combinations and arrangements of parts which are here- 20 inafter described, and set forth in the claims.

In the drawings illustrating my invention, Figure 1 represents a vertical longitudinal section. Fig. 2 is a plan or top view. Fig. 3 is a vertical cross-section on the line *x x*, Fig. 1.

25 Similar letters indicate corresponding parts.

The letter A designates a truck, comprising four wheels, B B, and having the forward wheel- 30 axle provided with means for attaching a draft-animal or power. In rear of the forward wheels B is located the plow C. This plow is at- 35 tached to a standard or upright, D, extending a certain distance above and below the truck-frame A. This standard D also offers bearings to the axles of pulleys E F, over which pass endless chains or belts G, to which the 40 scoops H are attached. The axle of pulleys F is provided with a gear-wheel, I, gearing into a gear-wheel, J, to which motion is imparted by the endless chain K, which chain in its 45 turn receives motion from one of the wheels B of the truck A. The truck is thus supplied with an elevator. These scoops H are toothed, as seen in Figs. 2 and 3, so that they are enabled to pass through the toothed rear edge 50 of the plow C and take up the substances which have thereon deposited themselves. From the plow the scoops H carry up their contents and deposit them on the chute L, which is also toothed at the edge nearest the 55 scoops H, so as to allow the teeth of the scoops to pass through. The chute L leads the material thereon deposited onto a distributor,

M. This distributor M is hung in bearings, and receives a reciprocating motion from the cam-lever N, which cam-lever is actuated by 55 the cam O on one of the wheels B. A spring, P, opposes the action of the cam O, thus se- 60 curing a reciprocating motion of the cam-lever N and distributor M. The distributor M is made to resemble a grate or coarse sieve, Fig. 2, and its reciprocating motion causes the earth and other foreign substances to be se- 65 parated from any products—as, for example, po- 70 tatoes—which may have been deposited on the distributor. The earth and foreign substances fall to the ground through that part of the dis- 75 tributor which is nearest to the chute L, while the potatoes or other products pass on along the chute, the finer ones falling through the chute into that compartment of the receptacle Q which is on one side of the partition R, while the coarser ones pass over the chute into the other compartment of said receptacle.

As will be seen from the arrangement of the apparatus, the products are caused to pass into 75 the receptacle Q almost entirely freed from earth and foreign substances.

To empty the compartments of the recep- 80 tacle Q, the hinged bottoms S, one being pro- 85 vided for each compartment, are allowed to swing down by means of the levers T. These levers T are each connected to one arm of bell- 90 crank levers U, which bell-crank levers swing on the body of the truck, while the other arm of each of the bell-crank levers is connected 95 to the free end of each of the hinged bottoms S.

It is also to be noted that the standard or upright D, to which the plow and the pulleys of the chain G supporting the scoops are hung, is perpendicularly movable, and is hung to one 90 arm of the bell-crank lever V, which bell-crank lever V swings on a fixed part of the truck A. By moving the lever W, to which the bell- 95 crank lever V is connected, in the proper di- 100 rection the standard or upright D is raised, the gear-wheel I is lifted out of gear with the gear-wheel J, and the operation of the ele- 100 vator ceases. The plow C is also at the same time raised. The gear-wheel J has its bearings in a fixed standard or part of the truck A, as shown in the drawings.

This apparatus is specially adapted for tak- 100 ing potatoes or other products out of or up from the ground and causing them to be col-

lected in a rapid manner and with small expenditure of labor.

What I claim as new, and desire to secure by Letters Patent, is—

- 5 1. The combination of a frame, A, mounted on supporting ground-wheels, a standard, D, connected with the frame to project above and below the same, a plow, C, toothed on the rear edge and attached to the lower end of the standard, the wheels E and F, supported by the standard above and below the frame, the elevator having toothed scoops H, the inclined delivery-chute L, toothed at its forward edge, the vibrating grate or sieve M at the lower end of the chute, and a potato-receiving receptacle supported by the frame under the discharge end of the grate or sieve, substantially as described.
- 10 2. The combination of the wheeled frame A, the standard D, vertically movable on the frame, and carrying a plow, C, having a toothed rear edge, the elevating mechanism having toothed pockets, means for raising and lowering the standard on the frame and thereby stopping and starting the elevator, and a delivery-chute, L, and vibrating grate or sieve M, both located adjacent to the upper end of the elevator, substantially as described.
- 15 3. The combination of the wheeled frame A, the standard D, movable vertically on the frame, and carrying at its lower end the plow C, having a toothed rear edge, the elevating-buckets having toothed scoops, and carried by the standard, and means for raising and lowering the standard and thereby stopping and starting the elevator, substantially as described.
- 20 4. The combination of the wheeled frame A,

the standard D, movable vertically thereon, the plow C, attached to the lower end of the standard, the elevating mechanism carried by the standard, the inclined delivery-chute L, located adjacent to the upper end of the elevator, and means for raising and lowering the standard from the driver's seat and thereby starting and stopping the elevator, substantially as described.

5. The combination, in a potato-digger, of a standard, D, vertically adjustable on the wheeled frame, and projecting above and below the latter, a plow, C, having a toothed rear edge and attached to the lower end of the standard, toothed elevating-buckets, and means for raising and lowering the standard in a vertical plane and thereby stopping and starting the elevating-buckets, substantially as described.

6. The combination of the wheeled frame A, the elevator driving-wheel J, mounted in fixed bearings on the frame, the standard D, vertically movable on the wheeled frame, and carrying at its upper end the gear-wheel F, the axis of which is provided with a gear-wheel, I, the elevating mechanism carried by the standard, and means for raising and lowering the standard to engage and disengage the said gear-wheels and thereby start and stop the elevator, substantially as described.

In testimony whereof I have hereunto set my hand and seal in the presence of two subscribing witnesses.

CHAS. G. WILTSE. [L. S.]
